UNITED STATES PATENT OFFICE.

JEROME W. WETMORE, OF ERIE, PENNSYLVANIA.

IMPROVEMENT IN RAIN-WATER CUT-OFFS.

Specification forming part of Letters Patent No. 137,268, dated March 25, 1873.

To all whom it may concern:

Be it known that I, JEROME W. WETMORE, of Erie, in the county of Erie and State of Pennsylvania, have invented certain Improvements in Cut-Offs for Rain-Water Pipes, of which the following is a specification:

The nature and object of my invention are as follows: Letters Patent of the United States No. 117,493 were granted to your petitioner and Cyrus Avery on the 25th day of July, 1871, for an improvement in cut-offs for rain-water pipes. The present improvement embraces simply a change in that invention in respect to the shaft, lever, or handle for turning the chute. The general construction of my cut-off is like that of Wetmore and Avery.

In the accompanying drawing, A A represent the greater part of the narrow sides of the box of the cut-off; B, the greater part of the top of the box, a narrow strip toward the observer being cut away; C, the side of the inlet-pipe, opposite to the observer; D and E, the like opposite sides of the outlet-pipes; F G R S, the lever or handle of the chute for changing it; H Z J K L, the chute with the side toward the observer corresponding with J R removed; I i, points where the handle F G passes through the top of the box; N, the

bridge partition on which the chute H Z rests. The chute as described is placed in position to throw the water into the side pipe E. F' G' S' R', the position of the handle; and H' Z' J' K' L', the position of the chute when they are changed to throw the water into the discharge-pipe D. This change is made by drawing upward on F G, and pressing at the same time lightly toward the inlet-pipe C. F G is bent to fit around the inlet-pipe.

The advantages of a handle of this form and position are, first, the freedom from leaking at the opening into the box; second, the favorable application of power to change the position of the chute so that its motion will not be prevented by non-use and rust; and third, the facility for repairing, and its not being liable to get out of repair.

I claim as my invention—

The handle F G R S of the chute of the rain-water cut-off attached to its upper end, and passing through the cover B of the box, substantially as and for the purpose specified.

JEROME W. WETMORE.
